Patent expires October 4, 1960

6 Claims: (Cl. 12—51)

1

This invention relates to pounding-up or hammering machines used in the manufacture of shoes.

Automatic pounding-up or hammering machines are not used to a larger extent in shoe manufacture, although manual hammering is a very tiresome and exhausting operation in view of the large number of shocks which are transmitted to the operator's body, because the automatic pounding-up machines of known construction show a number of disadvantages and have not entirely replaced the hand operation in which a skilled assistant treats each work piece according to any variations which may appear in the material and to the preceding treatment to which the work, that is the lasted upper, has been subjected. The main draw-back of the known machines consists in this, that in portions where the leather is thicker and/or in the case of faulty clamping of the last, the hammering of the uppers may result either in perforation of the leather at the border or, alternatively, in insufficient hammering, so that the operator then has to complete the hammering operation by hand. The clamping device has to be adjusted even for small variations in the size of the uppers to be treated, which circumstance leads to complications in the clamping device itself and in the machine as a whole and thus to expensive construction of the machine and to delays in the working process.

A further disadvantage of the known machines of this kind consists in that the hammers operate upon the upper always in the same position, or all parts of the upper are operated upon by the hammers with the same intensity, while in practice it is necessary to pound up the toe portion more strongly and over a wider area than the sides.

The new automatic pounding-up machine according to this invention eliminates the drawbacks of all known machines of the kind referred to and secures good results of manufacture even in the case of considerable variations and/or irregularities in the upper material.

The essential features of the invention consists in that with a fixedly mounted hammering drum and with automatic feed of the work carrying last into operating position, the feeding device for the last is arranged resiliently and yieldably in such a manner that the same is automatically brought to hammering position of the work carrying last in the two main directions of operative movement, that is in a direction at right angles to the surface of the drum

5 and in a direction toward the hammer. The last clamped in a holder receives an initial and a final impulse for its operative movement by means of a link mechanism from suitable cams or the like, but the appropriate adjustment of the work under the drum and toward the hammer is performed by the yieldable device just mentioned which adapts to the shape of the last the feeding movement of the work into its operating position. In this way accuracy in operation and safety of the hammering operation are secured, and thus it is possible to pound up shoes of any practical size without adjustment of the machine.

Other objects and advantages of the invention are disclosed in the following description with reference to the appendant drawings which show schematically and by way of example an automatic pounding-up machine constructed in accordance with the invention.

Fig. 1 shows the arrangement of the machine as a whole;

Fig. 2 shows the link mechanism of the operating column.

Fig. 3 shows the rotating device for the operating column; and

Fig. 4 is a view on a larger scale showing the construction of the hammering device.

A driving shaft 1 has secured thereon a number of discs provided with cam paths 2, 3, 4, 5 and 6. Motion is transmitted from the cam paths by means of suitable link mechanisms to an operating column 7 on which a holder 8 for the last 9 is adjustably mounted. The shaft 1 is mounted in the machine frame-work 10 and is driven by a motor (not shown) which is controlled by the foot lever 65. The hammering drum 11 is mounted on a shaft 66 within a closed bracket 12 secured on the frame 10. The hammer 15 is mounted rotatably on the shaft 66. The hammering drum revolves in the direction of the arrow. Dust from the hammering drum 11 is led away through pipe 13 to an exhaustor 14. Four main movements are imparted to the operating column 7, viz. a movement up and down, a movement forward and rearward, a rotary movement around its proper axis and a swinging movement from left to right and vice versa.

The up and down movement of the operating column 7 is derived from the cam path 2 by means of a roller 17 and a double-armed lever 16 provided on one end with a fork 18 and on the other end with a hinge 19 for connecting a spring 20, the lever 16 being rotatable around a pivot pin 21. The tension of the spring may be regulated

by means of a screw 22. The fork 18 controls a pin 23 on a shaft 24 which is guided at one end in a bushing 25 while its opposite end is connected by means of a universal joint 26 (Fig. 3) with the operating column 7. The column 7 is guided in a bearing 28 of the casing 27 (Fig. 1) which itself is mounted on a universal mount. The shaft 24 has secured thereon a toothed wheel 29 which transmits rotary movement from the cam path 3 to the operating column 7 (Fig. 3). Motion is transmitted by means of a roller 30 from the cam path 3 to a link 31 which is mounted in a guide 32 on the frame 10 and carries on its opposite end a rack 33. The rack 33 engages with a toothed sector 34 mounted rotatably on a pivot pin 35. To the sector 34 there is secured a second toothed sector 36 which also is rotatable around the pivot pin 35 and has its teeth in engagement with those of a spur wheel 29, whereby the column 7 is caused to rotate.

The forward and rearward movement of the operating column 7 is transmitted from the cam path 4 by means of a roller 37 to a double-armed lever 38 which is rotatable on a shaft 39 (Fig. 2) and has its opposite end connected by means of an universal joint 40 with a link 41. The link 41 passes freely through a spherical bearing 42 and at 43 is articulated to the casing 27 by means of which the motion of link 41 is transmitted to the operating column 7. The spherical bearing 42 is located in a frame 44 which is slideable in a recess provided in the head 45. The head 45 forms the one end of the double-armed lever 46 rotatable around a pivot pin 47 and to which swinging motion is imparted from the cam path 5 through a roller 48 on a link 49 which is rotatable on the shaft 39. The link 49 is connected by means of a rod 50 with a lever 51 rotatable on a pivot pin 52 and which by means of an adjustable pin 53 is connected to the other end of lever 46. The head 45 and with the same the link 41 and column 7 have imparted thereto swinging movement from left to right and in the opposite direction, the extent of such movement being adjustable by means of the shiftable pin 53 in accordance with the operations to be performed. By means of a hinge 54 the link 41 is connected with a spring 55, the tension of which may be varied by a screw 56.

The hammer 15 (Fig. 4) is provided with a heating element 57 (e. g. an electric or steam heated element) and is rotatable around a pivot pin 58 on an arm 59 which is mounted rotatably on a shaft 60. The arm 59 is caused to turn by a link 61 from the cam path 6 over a roller 62 and a lever 63 (Fig. 1) which is rotatable on the shaft 39. Operating motion is imparted to the hammer 15 in a manner known per se from a cam not shown which is mounted on the shaft 60 and is rotated in unison with the hammering drum 11 by means of an arm 64 (Fig. 4). The hammer 15 and arm 64 are spring loaded as shown at 66.

The machine operates as follows:

When the machine is inoperative the cams 2 and 4 keep the column 7 ineffective in a position towards the working station of the operator. As soon as the work carrying last 9 has been clamped in the holder 8 the operator depresses the foot lever 65 whereby the machine is started, so that the hammering drum 11 begins to revolve and also rotary motion is imparted to the driving cam shaft 1. The cam paths 2 and 4 for the two main movements, up and down, forward and rearward, are open and the rollers 17

and 37 of the respective levers 16 and 38 are forced thereagainst by means of springs 20 and 55. The tension of the springs 20 and 55 is active in the sense of forcing the operating column toward the hammering drum 11 and hammer 15. When the machine is out of operation, the cams 2 and 4 by means of their fingers neutralize the tension of the springs 20 and 55, whereby the column 7 is kept in a position remote from the hammering drum and hammer. Upon rotation of the shaft 1 and of the cams 2 and 4 the rollers 17 and 37 of the lever device leave the cam and this lever device is now entirely under the influence of the tension of springs 20 and 55, so that the column 7 carrying the last 9 is forced against the drum 11 and hammer 15.

As soon as the work carrying last 9 engages on the hammering drum and hammer, the pounding-up operation proper begins. By the effect of the cam paths 3 and 5 and of the corresponding link device, as above described, the operating column is caused to turn and swing to the required extent together with the work piece. Irrespective of the position of column 7, the work piece always sits and is hammered uniformly, the hammering action being constantly adapted by the tension of the springs 20 and 55 to the particular shape of the last, the thickness of the leather and to any other disturbing factor. In certain positions of the operating column 7—as required for correct hammering—the hammer 15 is caused to swing out of its original position by the cam path 6 and link mechanism 62, 63, 61 and 53, and this movement is followed by a corresponding movement of the last under the action of the tension springs 20 and 55, thereby changing the position where the hammering drum 11 operates. Through the rocking of the arm 59 on shaft 60, the hammer 15 is advanced or retracted with relation to the work piece, which latter at the same time is yieldingly urged into contact with the hammer by the spring 55. This bodily motion of the hammer mount toward or from the workpiece and resultant movement of the workpiece thus varies the effective intensity of the hammer blows on the workpiece even though the force of the hammer blows remains constant. In this way the hammering action is varied in intensity corresponding to the demand for correct hammering of the respective portions of the shoe which variation is of utmost importance when the toe portion of the shoe is being hammered.

From the foregoing description it clearly appears that under all conditions the engagement and therefore also the hammering action is adapted to the shape of the last, so that on the same machine it is possible to pound up left as well as right shoes and also various kinds and sizes of shoes without any construction changes in the machine. The adjustable tension of the springs 20 and 55 may be easily adapted to the quality and kind of leather.

If necessary, e. g. in the case of accident or the like, the operating column 7 may be moved by the assistant out of its working position during operation of the machine as the muscular force of the assistant is sufficient to overcome the spring tension.

The heated hammer in addition to its hammering action proper irons the work piece and in this way further improves the quality of the product.

It should be understood that the example shown and described of the automatic hammering machine has not any limiting character, as in the

various details of the same numerous changes may be made, without affecting the spirit of the invention as defined in the appendant claims.

What I claim is:

1. In an automatic hammering machine for use in the manufacture of shoes including a fixedly mounted hammering drum and a side beating hammer adjacent thereto, means for supporting a work piece to be operated upon by said hammering drum and hammer and for automatically feeding the same into various operating positions including spring means associated with said support and automatic feeding means for yieldingly engaging the work piece with said hammering drum and hammer during the movements through the various operating positions.

2. In an automatic hammering machine for use in the manufacture of shoes including a fixedly mounted hammering drum, means for supporting a work piece to be operated upon by said hammering drum and for automatically feeding the same into various operating positions comprising an upstanding casing mounted for universal movement, a column member journaled in said casing, a work support mounted on said column, means for moving said casing in various directions and for imparting rotary motion to said column and resilient means for yieldingly engaging the work piece with the hammering drum during the movement of said casing and column.

3. In an automatic hammering machine for use in the manufacture of shoes with a fixedly mounted hammering drum and automatic feeding of the work piece into operating position, an operating column enclosed within a casing, said casing being mounted for universal motion and having operating movements imparted thereto, a shaft connected by a universal joint with the column, a link mechanism associated with a cam path and an adjustable tension spring and imparting up and down movement to said column and a toothed wheel associated with toothed sectors, a rack and a cam path and imparting rotary movement to the column, the said two movements of the column being independent of the operating movements of the casing.

4. In an automatic hammering machine for use in the manufacture of shoes with a fixedly mounted hammering drum and automatic feeding of the work piece into operating position, an operating column enclosed within a casing, said casing being mounted for universal motion and having operating movements imparted thereto,

and a double-armed lever connected by means of an adjustable pivot pin with a further lever so as to vary the extent of the lateral movement of said casing.

5. In an automatic hammering machine for use in the manufacture of shoes including a fixedly mounted hammering drum, an oscillating hammer adjacent thereto and means for automatic feeding of the work piece into operating position, the provision of spring means associated with the device for feeding the work piece to operating position in such a manner as to move the work piece in the two main directions of operative motion, one of which is at right angles to the surface of the hammering drum and the other toward the hammer, thereby to bring the last into hammering position, and means for automatically shifting the operating position of said hammer in timed relation to the feeding of the work piece during the hammering operation.

6. In an automatic hammering machine for use in the manufacture of shoes including a fixedly mounted hammering drum, an oscillating hammer adjacent thereto and means for automatic feeding of the work piece into operating position, the provision of spring means associated with the device for feeding the work piece to operating position in such a manner as to move the work piece in the two main directions of operative motion, one of which is at right angles to the surface of the hammering drum and the other toward the hammer, thereby to bring the last into hammering position, a rotatable arm on which the hammer is mounted, a shaft carrying said rotatable arm and a link mechanism associated with a cam path and adapted to rotate the said arm.
